US0D1064858S

(12) **United States Design Patent** (10) Patent No.: **US D1,064,858 S**
(45) Date of Patent: ** Mar. 4, 2025

(54) **FIRE ALARM CONTROL PANEL**

(71) Applicant: **Honeywell International Inc.**,
Charlotte, NC (US)

(72) Inventors: **Sandesh Hemmuru Devaraja**,
Benguluru (IN); **Timothy Browne**, New
Haven, CT (US); **Scott Greco**,
Higganum, CT (US); **Vivek Kalyan**,
Bangalore (IN); **Unmesh Shankar
Kulkarni**, Aundh (IN)

(73) Assignee: **Honeywell International Inc.**,
Charlotte, NC (US)

(**) Term: **15 Years**

(21) Appl. No.: **29/891,190**

(22) Filed: **May 2, 2023**

(57) **CLAIM**

The ornamental design for a fire alarm control panel as shown and described.

DESCRIPTION

FIG. 1 is an angled perspective view of a fire alarm control panel embodiment of the present disclosure.

FIG. 2 is a front view of the embodiment of FIG. 1.

FIG. 3 is a left side view of the embodiment of FIG. 1.

FIG. 4 is a right side view of the embodiment of FIG. 1.

FIG. 5 is a top view of the embodiment of FIG. 1.

FIG. 6 is a bottom view of the embodiment of FIG. 1; and, FIG. 7 is an exploded view of the embodiment of FIG. 1. It is noted that broken lines are shown in the Figures for the purpose of illustrating portions of the fire alarm control panel and form no part of the claimed design.
